UNITED STATES PATENT OFFICE.

LOUIS J. GENETT, OF MARQUETTE, MICHIGAN.

TOY.

SPECIFICATION forming part of Letters Patent No. 620,908, dated March 14, 1899.

Application filed August 15, 1898. Serial No. 688,558. (No model.)

To all whom it may concern:

Be it known that I, LOUIS J. GENETT, a citizen of the United States, residing at Marquette, in the county of Marquette and State of Michigan, have invented a new and useful Toy, of which the following is a specification.

This invention relates to a toy.

The object of the invention is to produce an interesting, simple, and cheap toy commemorative of a historical event.

The invention consists, substantially, in the construction hereinafter described, and subsequently more particularly pointed out in the claim.

Like letters refer to the same parts in the several figures of the drawings, in which—

Figure 1 is a top view of the toy with the firing-head in cross-section and part of the handle in vertical section. Fig. 2 is a side elevation of the projectile and a vertical section of the handle. Fig. 3 is an elevation of a cane with the percussion device applied thereto.

It has been found that toys which by their construction and operation coupled with a proper name suggest a historical event are both interesting and instructive and serve to impress upon the minds of the people whatever event they suggest. The leading event preceding the present war between the United States and Spain, and the one event which probably more than any other rendered such war necessary, was the destruction of the United States battle-ship *Maine* in Havana harbor, Cuba, and a number of different tokens have been devised and placed upon the market commemorative of that event. It is the aim of the present invention to add to such store of tokens a toy which by its construction and operation will suggest the active remembrance of the *Maine*, which the armies and navies of the United States have indicated by their deeds.

The first feature of the invention consists of a holder or clamp for a percussion wafer or cap and adapted by impact against any reasonably hard surface to explode the percussion-cap. This holder or clamp devised for the percussion cap or wafer may be applied to any one of a great number of different articles. In the drawings it is shown applied to an arrow adapted to be projected by

suitable power against any hard surface, and also as applied to a cane for a similar purpose. The arrow, as shown in the drawings, 55 is adapted to be guided by a T-shaped handle, the horizontal portion of which is bored to permit the arrow to pass through and to which is secured an elastic band, as shown; but it is obvious that such arrow might be 60 projected by any other form of bow or other power, although the form shown has in practice been found very cheap and effective.

In the drawings the handle of the toy is lettered A, the arrow is lettered B, the clamping-holder for the percussion-cap is lettered C, and the elastic band is lettered D. Of course the T-shaped handle may be made of any suitable material; but it has been found in practice that wood is a cheap and efficient 65 material for the purpose and can be easily shaped in the desired manner. The arrow B may have its rear end reduced and flattened, as shown in Figs. 1 and 2, to afford a convenient grasping-surface. The elastic band 70 may be attached to the horizontal portion of the handle in a number of different ways; but I have found it convenient and cheap to attach it by forming a rabbet or recess at two 75 points on the outer surface of the horizontal portion of the handle, placing the two free ends of the elastic band in the rabbets or recesses thus formed and gluing a filling-block tightly upon the ends of the band and within such recess. The clamping-holder may also 80 be made in a variety of different ways; but I have found it cheap and convenient to make it of three parts—namely, a metal ferrule a, adapted to fit over the end of the arrow, cane, or other device to be projected, a hinged head 85 b, and a spring c. The spring is at one end suitably secured to the side of the ferrule and at the other end to the top of the head, so that such spring tends to keep the head closed or clamped tightly against the outer end of the 90 ferrule. A percussion cap or wafer e is to be inserted between the hinged head of the clamping-holder and the ferrule of the same.

In Fig. 3 the ferrule is slipped upon and secured to the lower end of a cane, the main 95 stem of which is marked B and the handle A and the parts of the clamping-holder as above.

It is obvious that many variations and

modifications may be made in the details of the construction without departing from the principle thereof.

What I claim, and desire to secure by Letters Patent, is—

A toy, comprising a handle, a main stem, a ferrule secured to one end of such stem, a clamping-head hinged at the edge thereof to the ferrule, and a percussion cap or wafer arranged to be held between such head and

ferrule and exploded when the head is projected against a hard surface; substantially as shown and described.

In witness whereof I have hereunto set my hand, this 13th day of August, 1898, in the presence of the subscribing witnesses.

LOUIS J. GENETT.
